FIG. 12

UNITED STATES PATENT OFFICE.

WALTER WRIGHT, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,271,821.

Specification of Letters Patent.

Patented July 9, 1918.

Application filed September 28, 1911. Serial No. 651,795.

To all whom it may concern:

Be it known that I, WALTER WRIGHT, a citizen of the United States, residing in New York city, in the county of New York and State of New York, have invented certain new and useful Improvements in Combined Type-Writing and Computing Machines, of which the following is a specification.

This invention relates to combined type-writing and computing machines, and is especially adapted to enable machines to be quickly altered to do writing which may require computation in several columns, and in which the position of said columns may vary from time to time with the particular style of work-sheet which is being written on. Such sheets are used in railroad offices.

The typewriting machine, as usual, comprises a letter-spacing traveling carriage to control the relation of the types to the work-sheet. The computing mechanism comprises a master wheel or denominational selector, which is arranged to successively engage a gang of wheels, which form a totalizer, in such a manner that the totalizer moves relatively to the master wheel with a step-by-step movement corresponding to the movement of the typewriter carriage. Thus the computing mechanism comprises one fixed and one traveling element. The extent of movement of the traveling element may be considerably less than that of the typewriter carriage, and the number of computing wheels is correspondingly considerably less than the number of letter-spaces in the travel of the typewriter carriage.

One purpose of the present invention is to enable columns of numerals at separated points in the travel of the typewriter carriage to be computed successively on adjacent groups of computing wheels, without having to have a large number of unused computing wheels between the various columns of numbers. For this purpose, the totalizer may be composed of a series of computing wheels and carry-over devices, which taken together may form a continuous train, and columns of figures may be computed in said train beginning at any selected computing wheels. To enable this to be done, a connection may be established between the traveling element of the computing mechanism and the typewriter carriage, so as to be at times effective and at times ineffective; with a result that some times the traveling

element of the computing mechanism moves concomitantly with the carriage of the typewriter, and at other times remains at rest.

This may be conveniently done by having the traveling element of the computing mechanism connected to a hook which is arranged to be intercepted by a tabulating stop or other tappet on the carriage of the typewriter. Until this hook is engaged by the stop of the tabulating mechanism, the typewriter carriage may travel alone, but when said stop catches said hook, the typewriter carriage and the traveling element of the computing mechanism may be arranged to travel together until a disconnector moves the hook positively out of engagement with said stop. There may be a series of stops similar to the one above described so arranged that each one successively will engage said hook, and be released therefrom. From this, it will follow that when the hook has been engaged by one stop and released therefrom, the traveling element of the computing mechanism will remain at rest until said hook is engaged by a second stop. In this way matter may be written on the work-sheet after the first computation is effected, and before the second one is begun, without in any way moving the traveling element of the computing mechanism, or to put it in other words, matter may be written over any desired number of letter spaces on a work-sheet, while the traveling element of the computing mechanism is in no way affecting the relation of the master wheel to the computing wheels.

In the form of the invention herein illustrated, it will be seen that the ordinary tabulator stops are employed which are settable manually at will along a rack bar, while a series of disconnectors may be permanently set at what is the preferred width for a column of figures in the totalizer. If a column of figures of extraordinary width is to be computed, one or more of the intermediate disconnectors may be set at ineffective position and the tabulating stop may, if desired, be shifted to correspond therewith.

An array of denominational key operated stops may be included as part of the tabulating mechanism, so that by suitable operation of the tabulating mechanism, the first figure written in any column may be automatically positioned denominational both in the totalizer and on the work-sheet.

Other features and advantages will hereinafter appear.

Reference may be had to the drawings in which—

5 Figure 1 is a fragmentary view in front elevation with parts broken away to show the underlying structure.

Fig. 2 is a fragmentary rear view in elevation.

10 Fig. 3 is a vertical section taken from front to rear with parts omitted for the sake of simplicity.

15 Fig. 4 is a fragmentary top plan view with portions cut away to show the underlying structure.

20 Fig. 5 is a detail view of the control for operatively disconnecting the traveling-element of the computing mechanism from the carriage, showing the same in its disconnected position as distinguished from that shown in Fig. 1, where the traveling element is operatively connected to the carriage.

25 Fig. 6 is a view similar to Fig. 5, showing the elements in a position other than that corresponding to the initial position of the traveling element of the computing mechanism.

30 Fig. 7 is a perspective view of certain of the elements shown in Figs. 5 and 6.

Fig. 8 is a fragmentary top plan view of a portion of the catch used in connecting the computing mechanism to the carriage, with one of the disconnectors for operatively disconnecting the catch from the stops.

35 Fig. 9 is a fragmentary view in elevation of the parts shown in Fig. 8, with the catch in the act of being disconnected from one of the stops.

40 Fig. 10 is a view of the parts shown in Figs. 8 and 9, after the catch has been disconnected from the stop, and showing the stop removing the trip from engagement with the tripper.

Fig. 11 is a fragmentary view of some of the parts shown in Figs. 9 and 10, showing the trip held in its inoperative position by the controller therefor.

45 Fig. 12 is a fragmentary top plan view of the mechanism shown in Fig. 11.

Fig. 13 is a fragmentary perspective view, showing the relative positions of the catch and one of the trips.

50 Referring more particularly to the separate parts of this invention as embodied in the form shown in the drawings, and as taken in connection with an Underwood typewriting machine, 1 indicates the key lever which operates through a sub lever 2

55 a type bar 3, so that the latter will strike rearwardly against the front side of a platen 4 mounted on a carriage 5. The carriage 5 is mounted to move in the usual manner on tracks 6 and 7, and is driven by a spring

drum 8. The carriage 5 is provided with a rack 9 mounted on pivoted arms 10, so as to be capable of moving into and out of engagement with a pinion 11 connected to an escapement wheel 12, the dogs which permit the movement of the latter at each stroke of a character key being omitted.

For the purpose of spacing the carriage for tabulating to different major columns or zones and digit columns in such zones, there are provided tabulating keys 13, the rear ends of which raise stop bars or plungers 14, provided at their upper ends with stop-engaging portions 15, which are adapted to be projected into the path of stops 16 by the movement of the tabulating keys 13. The stops 16 are shown to be bifurcated, so as to engage in slots 17 and 18 provided on the upper and lower surfaces of a bar or rack 19 carried by the carriage 5.

85 The bars 14 are each provided with a projection 114 which engages a universal bar 214 on a lever 314 connected by a link 414 to a lever 514 carrying a roller 614 adapted to engage under the rack 9, to lift the same from engagement with the pinion 11 at the operation of any of the tabulating keys 13.

90 The computing mechanism is of a type such as that described in the application of Wright and Degener No. 543,603, filed February 12, 1910, in which a master-wheel shaft 20 is rotated automatically at each depression of a numeral key a predetermined amount corresponding to the value of the particular numeral key. The rotation of the shaft 20 is transmitted in this case to a master wheel 21, which is shown as being mounted on an arbor 22 slidably splined on the shaft 20, the latter being shown as squared for this purpose. The master wheel 21, which is mounted on the arbor 22, is provided with teeth 23 which project between teeth 24, forming internal gears on disks 25; the latter are also provided with external teeth 26 which mesh with gears 27 provided with computing or numeral wheels 28.

95 Any suitable carry-over mechanism may connect each computing wheel with the one above, so that said one above is turned one unit when the lower one turns to read zero. With this carry-over mechanism the wheels in the totalizer form a continuous train. The arbor 22 is mounted to slide back and forth on the shaft 20, so that the master wheel 21 will engage successively with the juxtaposed disks 25, whereby the rotation of the shaft 20 will be transmitted successively to the several disks, and thus to the several computing wheels.

100 In order to permit this movement, the arbor 22 is in the form of a sleeve mounted on the shaft 20, so that it is capable of sliding back and forth in and out of the series of disks 25. To obtain the movement of the arbor, it is provided with an arm 30 which

slides on rods 29 and is connected with a rack 31 engaging a gear 32 mounted on a shaft 33. The shaft 33 extends to the rear of the machine, where it is provided with another gear 34 meshing with a gear 35, which latter engages with a rack bar 36 slidingly mounted in a channel guide 38, and further mounted by means of channel rollers 39 and 40.

10 The bar 36 has pivotally mounted thereon a catch or hook 41 which is adapted to engage any of the stops 16, or other stops, for the purpose of operatively connecting the rack bar 36 to the carriage 5. This mechanism just described may be termed "the connector of connecting mechanism" between the carriage and the movable elements of the computing mechanism, which in this instance consists of the arbor and master wheel.

15 In this instance, the catch 41 is shown as being provided with a tooth 42 which is spaced apart from a projection 43 by a slot 44 (Fig. 13), so as to form a notch into which any one of the stops 16 can fit, so as 20 to positively connect the catch to the carriage. The catch is normally held in its uppermost or active position by a spring 45 which engages at one end in a cavity 46 (Fig. 13), provided in the bar 36, and at the 25 other end with a pin 47 provided on the catch 41.

For the purpose of disconnecting the traveling element of the computing mechanism from the operative connection with the carriage at predetermined intervals in the movement of the carriage, there are provided a plurality of disconnectors 48 which are adapted to force the catch 41 from engagement with the particular stop 16 with 30 which it happens to be connected. While this operation might be accomplished by the direct engagement of the disconnectors 48 with the catch 41, for the purpose of obtaining a quick movement, it is desirable to 35 interpose a tripper 49, which is shown as pivotally mounted on the bar 36 adjacent the catch 41 and is provided with an arm 50 which projects over a finger 51 on the catch 41. When the tripper 49 reaches the discon- 40 nector 48, another arm 52 on the tripper 49 forming a bell crank lever, comprising a notch 53 is engaged by a toe 54 on a trip 55 of each of the disconnectors 48, thereby being swung, so that the arm 50 depresses the 45 catch 41 and frees it from the stop 16. The trip 55 is shown in the form of a lever pivoted intermediate its ends, and provided at the end opposite to that at which the toe 54 is located with a roller 56, whereby each of 50 the stops 16 may disengage the toe 54 from the tripper 49, after the trip 55 has accomplished its purpose of disconnecting the catch 41 from the same stop. This action is 55 shown clearly in Fig. 10, where the stop 16 is shown to have depressed one end of the

trip 55, raising the toe end from engagement with the tripper 49. A spring 57 is provided for each trip, which springs normally hold the trips 55 in such a position that the toes 54 thereon will be ready to engage the tripper 49. A spring 58 is also provided, which holds the tripper 49 in engagement with the finger 51 of the catch 41. The up and down movement of the catch, due to the spring 45 and the tripper 49, is limited by a pin 59 en- 60 gaging a slot 60 provided in the catch.

It will thus be seen when all of the trips 55 of the disconnectors 48 are held by the springs 57 in a position to engage the trippers 49, that inasmuch as these disconnectors 65 are mounted on a stationary portion of the frame, indicated at 61, as the tripper 49 and the catch 41 are carried successively toward these disconnectors 48 by the movement of the bar 36 to which they are connected, then 70 the catch 41 will be successively disengaged from the several stops 16 with which it has been successively connected on the continued movement of the carriage.

It is often desirable, however, to regulate 75 the times at which the connector for connecting the computing mechanism to the carriage shall be disconnected. For this purpose, each of the disconnectors 48 is provided with a control 62 which is adapted to render 80 its particular disconnector inoperative for the purpose of disconnecting the catch 41 from the stops 16. In this instance, the control is shown as embodying a shifter 63 having a depressed portion 64 and a raised 85 portion 65, the latter being adapted to engage a pin 66 provided on the toe end of the trip 55, so that when the shifter 63 is moved to the position illustrated in Fig. 11, the toe end of the trip 55 will be raised out of co- 90 operative alinement with the notch 53 of the tripper 49. The shifter 63 is arranged in such a manner that it will be automatically held or detained in either of its adjusted 95 positions, so as to permit the trip 55 to be 100 maintained in either of its positions without danger of accidental disarrangement. For this purpose, there is shown a lever 67 adapted to be manipulated by a handle 68, and pivotally mounted intermediate its ends in 105 any suitable manner, as by means of a pin 69. The lever 67 is adapted to operate the shifter 63 through the medium of a pin 70 secured to the shifter 63, said pin extending into a slot 71 provided in the lever 67. This 110 pin-and-slot connection also serves as a means to permit the detaining of the parts in any set position. Such detaining is effected by a spring 72 which is connected at one end to an extension 73 of the handle 68, 115 and at the other end to a pin 74, the latter being located at the opposite side of the pin 69 at which the extension 73 is located. The limit of movement of the shifter 63 in either 120 direction may be determined by the pin 74 125 130

engaging with a slot 75 in said shifter. It will be seen that when the lever 67 is in the position shown in Fig. 11, the spring 72 will extend along the line on one side of the pin 69, so as to hold the parts in the position shown in Fig. 11. When, however, the lever 67 is shifted, as by moving the handle 68 to the right in Fig. 11, there will at first be no movement of the shifter 63 as the handle 68 passes the line joining the pin 69 and the pin 74. As the lever 67 continues to move, however, the right-hand end of the slot 71, shown in Fig. 11, will engage the pin 70 and positively move the shifter 63 toward the left. This movement will continue until the right-hand end of the slot 75 of the shifter 63 engages the pin 74. In the meantime, the spring 72 is moved over to the right side of the pin 69 and exerts its tension to hold the parts in the position to which they have been moved, and which position is shown in Fig. 2. This, therefore, provides an automatic latch for securing the shifter and its actuating means in either position of adjustment.

For a final disconnector for disengaging the catch 41 from the stop 16 at the limit of capacity of the computing mechanism, there is provided a pin 76 which will always operate to engage the tripper 49 and thus depress the catch 41.

It is often desirable to provide manual means for disconnecting the computing mechanism from the typewriting carriage, as for example, when it is desired to do considerable typewriting without computing, which in this case may be accomplished by rotating the shaft 33 a sufficient amount when the master wheel 21 is at the beginning of its movement, to force a cam surface 77 provided on the catch 41 against a roller 78, whereby the catch 41 will be depressed out of engagement with one of the stops 16 with which it is in engagement at that time. If the catch does not happen to be in engagement with the stop, it will be depressed so that it cannot engage with any of the stops so long as the shaft 33 is rotated to its extreme position, as indicated in Fig. 5. This extreme backward rotation may be accomplished by a control 79, which is shown in the form of a lever 80 adapted to operate a pivotally mounted arm 81, which in turn engages, by means of a pin 82, a shoulder 83 provided in a raised disk 84 having a recess 85 cut therefor. The disk 84 is secured to the gear 32, which in turn is secured to the shaft 33, so that any movement of the pin 82, when the disk 84 is in the position shown in Fig. 1, will rotate the shaft 33 and the disk 84 to the position illustrated in Fig. 5. Here also a lost motion is provided between the lever 80 and the arm 81 by means of a pin 86 on the arm 81 engaging in an arcuate slot 87 provided in the lever 80. This lost

motion permits the parts to be latched or detained in either position of adjustment by means of a spring 88 which is secured at one end to the lever 80 and at its other end at such point beyond the pivot of the lever 80 that it will extend on opposite sides of the pivot in the two positions of adjustment of the lever 80. It is to be noted that this control for manually disconnecting the traveling member of the computing mechanism from the carriage can only be operated when the parts are in the position shown in Fig. 1, that is to say, before the commencement of a computation. This will be seen more clearly by reference to Fig. 6, where it will be seen that an attempt has been made to depress the lever 80 before the pin 82 has engaged shoulder 83, so the pin 82 has struck the circular surface of the disk 84, and is prevented from further movement because of the fact that the pivot of the arm 81 and the lever 80 is located eccentric with respect to the center of the shaft 33. It will be seen from Figs. 1 and 7, that the lever 80 and pivoted arm 81 are pivoted on a plate 80^a extending downwardly from the front of the typewriter frame in front of the gear wheel 32. The pin 82 rides in a slot 82^a in said plate 80^a.

It is desirable to exactly locate the master wheel 21 before the initial computation of each line, so that the carriage will properly advance the master wheel during the computing operation. For this purpose a positioner or aliner is provided, which is shown to embody a detent 89 in the form of a spring-pressed pin 90, which is beveled equally in both directions to engage a socket 91 provided in the rack bar 31. This detent is positive enough to hold the master wheel and some parts connected thereto in proper initial position, and yet permits the movement of these elements when they are positively manipulated by the letter-feeding movement of the carriage. In order to prevent rebound of these elements when they are returned to their starting position after each line, there is provided a shock-absorber 92 which is shown in the form of a piston buffer 93 yieldingly held in one position by a spring 94, the tension of which may be adjusted to a nicety, by means of an adjustment nut 95 engaging the screw threaded end 96 of the buffer 93. The particular position of the master wheel with respect to the numeral or computing wheels 28 may be indicated by a pointer 97 carried by the rack bar 31 and located in register with the master wheel 21.

Considering the operation of the device, it will be noted that the computing wheels 28 (Fig. 1) are divided into groups of three computing wheels, with a letter-space interval between groups. Such grouping is used in computing mere numbers, while if

dollars and cents were to be computed, other groupings might be used.

In the embodiment illustrated the disconnectors, or rather the trips 55, are so spaced 5 as to give a range for the traveling master wheel between each two disconnectors of two groups of three computing wheels or six computing wheels in all. Longer or shorter distances between trips 55 might be 10 used to give larger or smaller ranges. That is to say, in the present illustration, this gives a capacity of 999,999 for each computing zone or major column between disconnectors. The first major column may be 15 made considerably larger depending on the distance of the first picking up stop 16 from the point of disconnection by the first trip 55. If larger intermediate computing zones or columns than six digits are desired with 20 this spacing of the trips 55 after the first major column or zone, one or more of the trips 55 can be silenced. The stops 16 which are to pick up the catch 41, and thus the master wheel, are so set on the rack bar 19 25 that they will engage the catch 41 at the beginning of the computing zone so that if necessary a number of six-digit magnitude, such as 123, 123, could be computed between every two disconnectors. However, ordinary 30 numbers of this magnitude would not be computed, and although the stop 16 picks up the master wheel at the beginning of the zone, it will travel idly for one or more letter spaces according to the magnitude of 35 the number being computed, and also to allow at least one letter space for tens carrying. The initial digit column computed in will depend on the particular tabulating or plunger stop 14 which comes up into the 40 path of the carriage-carried stop 16 which is by this time in engagement with the hook or latch 41.

In Fig. 2 the carriage is shown as traveling after having engaged one of its stops 45 16 with the latch 41, so that the master wheel is traveling with the carriage. The particular digit column or letter space in this computing zone at which the carriage stops and at which the master wheel stops 50 for the first digit to be typewritten and computed, will depend upon the particular tabulating or plunger stop 14 raised to intercept the carriage stop 16. As each successive digit is typewritten and computed the 55 carriage will move step by step toward the right in Fig. 2. The catch 41 will be drawn along with the carriage, and thus likewise the rack bar 36. This movement will rotate the gear 34 through the intermediary of the 60 gear 35, and thus rotate the shaft 33 which rotates the gear 32 located at the front of the machine, and meshing with the rack 31. The rack 31 is thus advanced so that it carries the arbor 22 and the master wheel 21 65 through the series of disks 25 step-by-step

at each stroke of a numeral key, so that said master wheel is brought successively in cooperation with the internal gear on each disk. Inasmuch as the shaft 20 is being rotated, by mechanism not shown, predetermined amounts corresponding to the particular numeral keys being struck, the master wheel will rotate the disks 25 corresponding amounts, so that the numeral wheels 28 will be turned to the same extent, through the 70 intermediary of the gears 27.

Considering Fig. 2 again, it will be seen that when the carriage has traveled to such a distance that the tripper 49 carried by the 80 rack bar 36 comes in engagement with the toe 54 of the trip 55, said tripper will be rocked on its pivot point, so as to depress the catch 41 and withdraw it from engagement with the stops 16. A further movement of the carriage will bring this particular stop 16 in engagement with the roller 56 of the particular disconnector 48, and rock the trip 55 so that the toe 54 thereon will be removed from engagement with the notch 53, whereby the tripper 49 and the catch 41 90 are permitted to return to their normal positions, as indicated in Fig. 10.

The rack bar 36 and the remainder of the connector or transmitter now remains passive, thus holding the master wheel 21 passive during a certain portion of the subsequent movement of the carriage 5. The extent of this passive movement of the carriage, that is to say, without manipulating the traveling element of the computing 95 mechanism, will be determined by the position of the next stop 16. When this next stop comes in contact with the catch 41, it will force the same down and engage in the seat provided therein, so that the master 100 wheel of the computing mechanism will traverse the next series of computing disks. The point at which this next stop is set will determine the beginning of the next computing zone. During the first connection of 110 the catch to the first stop the machine may have been calculating a numeral in one column of figures or computing zone, and between the disconnection of the catch from the first stop and its connection with the second stop the machine may have been used to insert explanatory notes or merely give a long space on the work-sheet. When the second stop carries the catch along with it, and thus feeds along the traveling element 115 of the computing mechanism, the computing may again be carried on. The computation does not necessarily begin at the computing wheel in register with the master wheel at the instant of pick up by the stop 16, but 120 may be started at any succeeding computing wheel in this zone depending generally on the selection by the operative who strikes a particular key 13 and brings into play the desired one of the plunger stops 14, to de- 130

termine the first stopping of the master wheel in the zone, depending on the number of digits in the number being computed in this zone. Inasmuch as the first movement 5 of the catch with the carriage has carried it beyond the first disconnector 48, the point of disconnection of the catch from the second stop will be determined by the location of the next active disconnector 48. This 10 may be the second one counting from left to right in Fig. 2, or the third, fourth and so on.

If it is not desired to disconnect the catch at the interval of movement of the carriage 15 corresponding to the distance between the first and second disconnectors, it is merely necessary to silence or disable the second disconnector, and the third, fourth, and so on, if also desired, as has been explained above.

20 This is done by shifting the control for the disconnector so that the toe 54 on the trip thereof is raised out of alignment with the shoulder on the tripper 49. The next operative disconnector will therefore trip the 25 catch 41 from engagement with the second stop, so that the traveling element of the computing mechanism, which in this case is the master wheel, will remain passive once more, while the carriage is permitted to 30 move on during the spacing thereof during major columns or computing zones, or for the purpose of interspersing typewritten matter between the columns of figures to be computed. This action continues, each suc- 35 cessive stop 16 engaging with the catch 41, so that the movement of the carriage is utilized to move the traveling element of the computing mechanism the desired extent, which is determined by the distance between 40 the last disconnector in action and the next active disconnector. Of course it is to be understood that any of these disconnectors, even the first, can be rendered inactive, and in fact all of them can be rendered inactive 45 if so desired.

When the carriage reaches the limit of its travel to the right in Fig. 2, the final dis- 50 connector 76, shown in the form of a pin, will engage the tripper 49 and shift the catch 41 out of engagement with the stop with which it happens to be connected. On the return movement of the carriage toward the left in Fig. 2, for a new line, the first stop 16 coming in contact with the catch 41 55 will engage the tooth 42 on the right hand side somewhat in the position illustrated in Fig. 10, and will carry the catch 41 and the bar 36 back with it toward the left until the inclined surface 77 at the rear of the catch 60 41 comes in engagement with the throwout roller 78, when the catch will be disengaged from the stop, and the carriage permitted to travel to its starting position. Any sub- 65 sequent stops passing over the catch 41 will merely force the catch down against the ten-

sion of the spring 45, so that it wavers back and forth.

It will be seen that this movement returns the traveling element of the computing mechanism, that is, the master wheel 21, to 70 its extreme left hand position, as viewed in Fig. 1, where it will be caught in the position just ready to enter the initial disk of the computing mechanism. The shock absorber 92 is nicely tensioned so that there will be 75 little or no bounce or jar of the master wheel as it returns with the carriage, although the carriage may continue its return movement after the master wheel has finished its return movement. Any little bounce or mal- 80 adjustment which is evident will be taken up by the positioner 89, so that the starting point of the master wheel for a new line will be accurately determined.

The action is repeated over again at the 85 new line, the catch being alternately connected to the carriage and disconnected therefrom, so that the master wheel is alternately fed step-by-step through the computing disks and allowed to remain passive 90 between the successive points of computation or computing zones determined by the position of the stops 16 and the active disconnectors 48. If it is desired at any time to entirely disconnect the computing mech- 95 anism from movement with the carriage, so that the typewriting mechanism can be used without shifting the traveling element of the computing mechanism, it is merely necessary to throw the lever 80 from the position indicated in Fig. 1 to the position in- 100 dicated in Fig. 5, which, however, can only be done when the master wheel is at its initial position to the extreme left of the computing casing, as indicated in Fig. 1. This movement will shift the disk 84 by engage- 105 ment of the pin 82 with the shoulder on said disk, so that the shaft 33 is rotated an ab- normal amount toward the left, whereby the catch 41 is thrown against the throwout 110 roller 78, whereby the catch will be cammed down out of engagement with the stops 16, and in fact so far down that it cannot en- gage with any of said stops during the movement of the carriage.

Inasmuch as the lever 80, as illustrated in Fig. 5 is automatically held by the spring 88, the parts will be thus automatically maintained in disconnected position until positively rearranged by a manipulation of 120 the lever 80. The spring 88 also acts as will be seen in Fig. 1 to hold the lever in operative position by the swinging of the spring 88 to the opposite side of the pivot of the lever 80.

Having thus described my invention, I claim:

1. The combination with typewriting mechanism including a carriage, of computing mechanism including a traveling ele- 130

- ment, a connector for connecting said traveling element with said carriage so as to obtain a concomitant movement of said carriage and said traveling element, and a series of disconnectors for rendering said connector inoperative, for the purpose of connecting the carriage and the traveling element, at predetermined points in the movement of said carriage.
- 10 2. The combination with typewriting mechanism including a carriage, of computing mechanism including a traveling element, a connector for connecting said traveling element with said carriage so as to obtain a concomitant movement of said carriage and said traveling element, a series of disconnectors for rendering said connector inoperative, for the purpose of connecting the carriage and the traveling element, at predetermined points in the movement of said carriage, and means for rendering one or more of said disconnectors inoperative.
- 15 3. The combination with typewriting mechanism including a carriage, of computing mechanism including a traveling element, a connector for connecting said movable element with said carriage so as to obtain a concomitant movement of said carriage and said traveling element, a series of disconnectors for rendering said connector inoperative, for the purpose of connecting the carriage and the traveling element, at predetermined points in the movement of said carriage, and individual controls for governing the action of said disconnectors.
- 20 4. The combination with a typewriting mechanism including a carriage, of a computing mechanism including a traveling element, a transmitter for imparting the movement of said carriage to said traveling element, and a series of disconnectors operating successively to interrupt the movement of said element by said carriage at predetermined points in the movement of said carriage.
- 25 5. The combination with a typewriting mechanism including a letter feeding carriage, of a computing mechanism including a traveling element, a bar connected to said traveling element, a bar intermittently connectible to said carriage during a continuous movement thereof, and gearing for driving said first-mentioned bar from said second-mentioned bar.
- 30 6. The combination with a typewriting mechanism including a letter feeding carriage, of a computing mechanism including a traveling element, a rack bar connected to said traveling element, a gear meshing with said rack bar, a rack bar intermittently connectible to said carriage during a continuous movement thereof, a gear drivingly connected to said first-mentioned bar, and a gear engaging said second-mentioned rack bar, whereby the movement of said first-mentioned rack bar may be transferred to said second-mentioned rack bar.
- 35 7. The combination with a typewriting mechanism including a letter feeding carriage, of a computing mechanism including a traveling element, a rack bar connected to said traveling element, a rack bar intermittently connectible to said carriage during a continuous movement thereof, and gearing connecting said first-mentioned rack bar to said second-mentioned rack bar in such a manner that the movement of one will be translated in the movement of the other in the opposite direction.
- 40 8. The combination with typewriting mechanism including a letter feeding carriage, of computing mechanism including a traveling element, a rack bar connected to said traveling element, a gear meshing with said rack bar, a shaft connected to said gear, a gear on said shaft, a gear meshing with said second-mentioned gear, and a rack bar intermittently connectible to said carriage during a continuous movement thereof meshing with said last-mentioned gear, whereby the movement of said carriage and said movable element may be carried on concomitantly.
- 45 9. The combination with a typewriting mechanism including a carriage, of a computing mechanism including a traveling element, a rack bar connectible so as to be movable with said carriage, a rack bar connected to said traveling element, gearing between said rack bars, and a series of disconnectors adapted to successively interrupt the connection of said first-mentioned rack bar with said carriage.
- 50 10. The combination with a typewriting mechanism including a carriage, of a computing mechanism including a traveling element, a rack bar connectible so as to be movable with said carriage, a rack bar connected to said traveling element, gearing between said rack bars, a series of disconnectors adapted to successively interrupt the connection of said first-mentioned rack bar with said carriage; and means for controlling the action of said disconnectors.
- 55 11. The combination with a typewriting mechanism including a carriage, of a computing mechanism including a traveling element, a connector for connecting said carriage with said traveling element, so that the movement of these two will be concomitant, a disconnector for interrupting the action of said connector so as to permit said carriage and said traveling element to be independent of each other, and an interponent adapted to act as an intermediary between said connector and disconnector for accomplishing the interruption of the connection between said traveling element and said carriage, said disconnector being automatically operable to disconnect itself from

said interponent after its actuation of the same.

12. The combination with a typewriting mechanism including a carriage, of a computing mechanism including a traveling element, adjustable stops for controlling the connection of said traveling element with said carriage, and adjustable disconnectors for controlling the disconnection of said traveling element and said carriage.

13. The combination with a typewriting mechanism having a carriage, of a computing mechanism having a traveling element, said carriage and said traveling element being connectible to move concomitantly, stops for controlling the connection of said traveling element with said carriage, and disconnectors for controlling the disconnection of said traveling element and said carriage, said disconnectors being operable by said stops.

14. The combination with a typewriting mechanism having a carriage, of a computing mechanism having a traveling element, a catch for connecting said traveling element with said carriage so that said carriage and said traveling element can move concomitantly, a plurality of stops connected to said carriage and engaging with said catch, and a series of trips for disengaging said catch from said stops, said trips being arranged to be manipulated by said stops.

15. The combination with a typewriting mechanism including a carriage, of a computing mechanism including a traveling element, a catch for connecting said traveling element with said carriage, a series of stops carried by said carriage and arranged to engage said catch, a tripper for disconnecting said catch from said stops, and a series of trips arranged to engage said tripper at different times to operate the same to release said catch.

16. The combination with a typewriting mechanism including a carriage, of a computing mechanism including a traveling element, a catch for connecting said traveling element with said carriage, a series of stops carried by said carriage and arranged to engage said catch, a tripper for disconnecting said catch from said stops, and a series of trips arranged to engage said tripper at different times to operate the same to release said catch; said trips lying in the path of travel of said stops so as to be operable thereby.

17. The combination with a typewriting mechanism including a carriage, of a computing mechanism including a traveling element, a catch for connecting said traveling element with said carriage so that the movement of one may be imparted to the other, a tripper for manipulating said catch to control the connection of said traveling element with said carriage, a trip for actuating said

tripper, and a stop for connecting said catch to said carriage and for releasing said trip from engaging with said tripper after the former has actuated the latter.

18. The combination with a typewriting mechanism including a carriage, of a computing mechanism including a traveling element, a catch for connecting said traveling element with said carriage so that the movement of one may be imparted to the other, a tripper for manipulating said catch to control the connection of said traveling element with said carriage, a series of trips for successively actuating said tripper to control the connection of said traveling element with said carriage, and a series of stops for successively completing the connection between said carriage and said traveling element by engagement with said catch and also acting to successively disengage said trips from said tripper.

19. The combination with a typewriting mechanism including a carriage, of a computing mechanism including a traveling element, a catch for connecting said traveling element with said carriage so that the movement of one may be imparted to the other, a tripper for manipulating said catch to control the connection of said traveling element with said carriage, a series of trips for successively actuating said tripper to control the connection of said traveling element with said carriage, and a series of stops for successively completing the connection between said carriage and said traveling element by engagement with said catch and also acting to successively disengage said trips from said tripper; said stops being adjustable to vary the instants of connection of said traveling element with said carriage.

20. The combination with a typewriting mechanism including a carriage, of a computing mechanism including a traveling element, a catch for connecting said traveling element with said carriage so that the movement of one may be imparted to the other, a tripper for manipulating said catch to control the connection of said traveling element with said carriage, a series of trips for successively actuating said tripper to control the connection of said traveling element with said carriage, and a series of stops for successively completing the connection between said carriage and said traveling element by engagement with said catch and also acting to successively disengage said trips from said tripper; said stops being adjustable to vary the instants of connection of said traveling element with said carriage.

21. The combination with a typewriting mechanism including a carriage, of a computing mechanism including a traveling element, a catch for connecting said traveling

element with said carriage so that the movement of one may be imparted to the other, a tripper for manipulating said catch to control the connection of said traveling element 5 with said carriage, a series of trips for successively actuating said tripper to control the connection of said traveling element with said carriage, and a series of stops for successively completing the connection between 10 said carriage and said traveling element by engagement with said catch and also acting to successively disengage said trips from said tripper; said trips being adjustable to vary the period of connection of said traveling element with said carriage.

22. The combination with a typewriting mechanism including a carriage, of a computing mechanism including a traveling element, said traveling element being connectible with said carriage, a trip for interrupting the connection of said traveling element with said carriage, a control for said trip embodying a shifter adapted to manipulate said trip from one position to another, and a 25 lever for operating said shifter.

23. The combination with a typewriting mechanism including a carriage, of a computing mechanism including a traveling element, said traveling element being connectible with said carriage, a trip for interrupting the connection of said traveling element with said carriage, a control for said trip embodying a shifter adapted to manipulate said trip from one position to 30 another, a lever for operating said shifter, and means for connecting said lever with said shifter so as to lock said shifter in its different positions of adjustment.

24. The combination with a typewriting mechanism including a carriage, of a computing mechanism including a traveling element, connections between said traveling element and said carriage, whereby said traveling element and said carriage may 40 move concomitantly, a trip for interrupting the connection of said carriage with said traveling element, a shifter for controlling the position of said trip, a lever for manipulating said shifter, and a spring for 45 holding said shifter and said lever in either position of relative adjustment.

25. The combination with a typewriting mechanism including a carriage, of a computing mechanism including a traveling element, connections between said traveling element and said carriage, whereby said traveling element and said carriage may move concomitantly, a trip for interrupting the connection of said carriage with said 50 traveling element, a shifter for controlling the position of said trip, a lever for manipulating said shifter, and a spring for holding said shifter and said lever in either 55 position of relative adjustment; said lever 60 and said shifter having a lost motion con-

nexion with each other, so as to allow the swinging of said spring from one locking position to another locking position.

26. The combination with a typewriting mechanism including a carriage, of a computing mechanism including a traveling element, connections between said carriage and said traveling element permitting said carriage and said traveling element to move concomitantly, a trip for interrupting the 70 connections between said traveling element and said carriage, a shifter for manipulating said trip embodying an arm having depressed and raised portions adapted to engage with said trip, and a lever for manipulating said shifter.

27. The combination with a typewriting mechanism including a carriage, of a computing mechanism including a traveling element, connections between said carriage and said traveling element permitting said carriage and said traveling element to move concomitantly, a trip for interrupting the 75 connections between said traveling element and said carriage, a shifter for manipulating said trip embodying an arm having depressed and raised portions adapted to engage with said trip, a lever for manipulating said shifter, a pin-and-slot connection between said lever and said shifter permitting a lost motion between the two, and a spring connected to said lever in such a manner as to swing alternately to opposite 80 sides of the fulcrum thereof so as to lock said lever in either position of adjustment. 90

28. The combination with a typewriting mechanism including a carriage, of a computing mechanism including a traveling element, connections between said carriage and said traveling element including a 105 catch, a tripper for manipulating said catch, a trip for manipulating said tripper, said trip embodying a lever pivotally mounted intermediate its ends and provided at one end with a toe adapted to engage said tripper and at the other end with a roller, and one or more stops for engagement with said catch to assist in the connection of said traveling element with said carriage and for removing said trip from engagement with 110 said tripper by acting on said roller.

29. The combination with a typewriting mechanism including a carriage, of a computing mechanism including a traveling element, a connector extending between said 120 traveling element and said carriage to cause them to move concomitantly, a control for rendering said connector inoperative, and a series of disconnectors for rendering said connector inoperative.

30. The combination with a typewriting mechanism including a carriage, of a computing mechanism including a traveling element, a connector forming means for causing the concomitant movement of said 130

- carriage and said traveling element, a series of stops adapted to successively engage said connector to complete the connection between said traveling element and said carriage, a series of disconnectors for disengaging said connector from said stops, and a control for moving a certain part of said connector from coöperative relation with respect to said stops.
- 10 31. The combination with a typewriting mechanism including a carriage, of a computing mechanism including a traveling element, a connector forming means for causing the concomitant movement of said carriage and said traveling element, a series of stops adapted to successively engage said connector to complete the connection between said traveling element and said carriage, a series of disconnectors for disengaging said connector from said stops, a control for moving a certain part of said connector from coöperative relation with respect to said stops, and means for locking said connector in either position of adjustment.
- 15 32. The combination with typewriting mechanism including a carriage, of a computing mechanism including a traveling element, a connector for joining said carriage and said traveling element so that they will move concomitantly, and means for rendering said connector inoperative, said means being actuatable at a single position of adjustment of said traveling element and 20 inoperative at other positions of adjustment of said traveling element.
- 20 33. The combination with a typewriting mechanism including a carriage, of a computing mechanism including a traveling element, a connector for causing the concomitant movement of said carriage and said traveling element, and a control for rendering said connector operative and inoperative; said control including means for preventing the operation thereof at certain 25 points in the movement of said traveling element.
- 25 34. The combination with a typewriting mechanism including a carriage, of a computing mechanism including a traveling element, a connector for causing the concomitant movement of said carriage and said traveling element, a control for rendering said connector operative and inoperative; said control including means for preventing the operation thereof at certain points in the movement of said traveling element; and means for holding said control in either 30 position of adjustment.
- 30 35. The combination with a computing mechanism including a traveling element, of a typewriting mechanism including a carriage, a rack bar connected to said traveling element, a gear meshing with said rack bar, 35 and a disk having a notch therein operatively

connected to said gear, a catch traveling concomitantly with said gear and adapted to be connected to said carriage, a pin adapted to engage said notch in said disk to manipulate said catch, and means for manipulating said pin.

36. The combination with a typewriting mechanism including a carriage, of a computing mechanism including a traveling element, a connector between said traveling element and said carriage, whereby they may travel concomitantly, said connector including a gear and a catch connected to said gear, a circular disk connected to said gear and provided with a recess at a certain point in its periphery to form a shoulder, an arm pivoted eccentric with respect to the center of said disk, a pin carried by said arm adapted to engage said shoulder at certain relative positions of said arm and said disk, and means for manipulating said arm whereby said pin can operate said disk.

37. The combination with a typewriting mechanism including a carriage, of a computing mechanism including a traveling element, a connector between said traveling element and said carriage, whereby they may travel concomitantly, said connector including a gear and a catch connected to said gear, a circular disk connected to said gear and provided with a recess at a certain point in its periphery to form a shoulder, an arm pivoted eccentric with respect to the center of said disk, a pin carried by said arm adapted to engage said shoulder at certain relative positions of said arm and said disk, means for manipulating said arm whereby said pin can operate said disk, and means for locking said last-mentioned means in a plurality of adjusted positions.

38. The combination with a typewriting mechanism including a carriage, of a computing mechanism including a traveling element, a connector between said carriage and said traveling element whereby said carriage and said traveling element may be caused to travel concomitantly, a plurality of disconnectors for interrupting the connection between said traveling element and said carriage, said disconnectors being adjustable to active and inactive positions, and a fixed disconnector for interrupting the connection between said traveling element and said carriage at the end of the linear computation.

39. In a combined typewriting and computing machine, the combination with a letter-feeding carriage, of a totalizer having fewer denominational wheels than the letter spaces in said typewriting mechanism, a master wheel arranged to be engaged *serially* by the wheels of said totalizer, settable stops for connecting said carriage and said master wheel at different points to have a concomitant movement, and disconnectors

corresponding to said stops settable to disconnect said carriage and said computing mechanism.

40. In a combined typewriting and computing machine, the combination with a letter feeding carriage and a totalizer having considerably fewer dial wheels than the letter-spaces of said carriage, of a master wheel for turning said wheels *seriatim*, tabulating 10 stops for positioning the carriage of said typewriter and simultaneously causing said master wheel and computing wheels to have their *seriatim* engagements, and a series of spaced disconnectors arranged to disconnect 15 said computing mechanism and typewriter carriage, at a plurality of letter spaces distant from the point at which their connection was established.

41. In a combined typewriting and computing machine, the combination of computing devices, and settable means for determining the identical width of various computing columns computed thereby, effective to double the width of said columns by making ineffective certain of said determining 25 means.

42. In a combined typewriting and computing machine, the combination with a traveling carriage and numeral keys, of a 30 totalizer comprising a gang of computing wheels, forming a train, means for selectively grouping said wheels into a plurality of groups, and means for causing said groups to correspond to the selected columns on said 35 carriage, all of said means acting by connecting and disconnecting said totalizer to travel at different times with said carriage.

43. In a combined typewriting and computing machine, the combination with a 40 traveling carriage and numeral keys, of a totalizer comprising a gang of computing wheels forming a train, means for selectively grouping said wheels into a plurality of groups, and a rack bar comprising coupling devices on said carriage to cause said 45 groups to correspond to selected columns on said carriage.

44. In a combined typewriting and computing machine, the combination with a 50 traveling carriage and numeral keys, of a totalizer comprising a gang of computing wheels, forming a train, means for selectively grouping said wheels into a plurality of groups, and a tabulating mechanism for said 55 carriage comprising stops arranged to couple said gang to said carriage at selected points.

45. In a combined typewriting and computing machine, the combination with computing wheels forming a totalizer long 60 enough to be utilized as groups forming a plurality of small totalizers, of a traveling typewriter carriage, means settable to utilize one group of said wheels to print in one column of said typewriter, means settable to 65 use adjacent groups of said wheels to com-

pute matter printed in a non-adjacent column of said typewriter, and means for merging two groups to make a greater group, all of said means acting by determining different periods of travel of a part of 70 the totalizer with the carriage.

46. In a combined typewriting and computing machine, the combination with computing wheels and carry-over devices forming a totalizer long enough to be utilized as 75 groups forming a plurality of small totalizers, of a denomination selector to utilize one group of said wheels to compute while printing in one column of said typewriter, means for connecting said denomination selector to compute in an adjacent group of 80 said wheels matter printed in an adjacent or a non-adjacent column of said typewriter, and means for disconnecting said selector at the end of said column.

47. In a combined typewriting and computing machine, the combination with computing wheels and carry-over devices forming a totalizer long enough to be utilized as groups forming a plurality of small totalizers, of a denomination selector to utilize one group of said wheels to compute while printing in one column of said typewriter, means for connecting said denomination selector to compute in an adjacent group of 90 said wheels matter printed in an adjacent or a non-adjacent column of said typewriter, means for disconnecting said selector at the end of said column, and means settable to cause said denomination selector to be effective on both said groups as though they 100 formed a single group.

48. In a computing machine, the combination with a traveling carriage and a stop thereon, of a hook adapted to be caught by 105 said stop, means settable to disconnect said hook from said stop, and an extension for said disconnecting means operated by said stop to make said disconnecting means ineffective.

49. In a computing machine, the combination with a traveling carriage and a stop thereon, of a hook adapted to be caught by 110 said stop, means settable to disconnect said hook from said stop, and a fixed stop adapted to make said disconnecting permanently effective.

50. In a computing machine, the combination with a traveling carriage and a rack bar thereon, of a stop on said rack bar, a hook adapted to be caught by said stop to be carried along thereby, a trip for disconnecting said hook from said stop, a disconnecter for operating said trip, and an extension for said disconnecter operable by 115 said stop to make said disconnecter ineffective.

51. In a computing machine, the combination with a traveling carriage and a rack bar thereon, of a stop on said rack bar 120

130

hook adapted to be caught by said stop to be carried along thereby, a trip for disconnecting said hook from said stop, a swinging disconnector for operating said trip, and a 5 fixed disconnector effective on said trip.

52. The combination with a traveling carriage having a length and travel corresponding to the length of the desired line of a given number of digit columns or letter 10 spaces, of two primary elements, to wit, a totalizer having a series of computing wheels, and a master wheel, said elements having a relative movement to enable said master wheel to come into *seriatim* register 15 with each of said computing wheels, said totalizer having fewer computing wheels than the available digit columns or letter spaces of said carriage, and traversing means for effecting periods of step-by-step relative 20 movements between said primary elements for successive groups of said computing wheels concomitant with step-by-step movements of said carriage, and intermixing between the groups of step-by-step relative 25 movements, periods of rest while said carriage continues its movement.

53. The combination with two primary elements, to wit, a totalizer having a plurality of computing wheels which may be 30 used in groups, each of which groups forms a distinct computing unit, and a master wheel for driving the wheels of said totalizer, of a platen carriage traveling to determine different computing zones or major 35 columns and having an available range or length of writing line or number of letter spaces considerably greater than the number of computing wheels in said totalizer, one of said primary elements traveling 40 relatively to the other to enable the successive registering of said master wheel with each of said computing wheels, a connection for automatically effecting a concomitant movement of said traveling element with 45 said carriage, and means for controlling said connection, so as to give for a continuous travel of said carriage for a line of writing, periods of synchronized step-by-step 50 movements of said traveling element with said carriage, with intervening periods of rest for said traveling element, the continued movement of said traveling element aggregating the range of said totalizer, the periods of rest allowing for the difference in 55 range between the carriage and the totalizer.

54. The combination with two primary elements including a totalizer having a series of computing wheels arranged to be 60 variously grouped so as to afford one or more computing units of variable magnitude, and a master wheel for driving said computing wheels *seriatim*, one of said ele-

ments traveling to enable the *seriatim* registering of said master wheel with each of said 65 computing wheels, of a traveling carriage, a connection between said carriage and said traveling element, silencing means for said connection to determine the magnitude of a computing zone or column, and silencing 70 means for said silencing means operating to increase the magnitude of a computing zone or column.

55. The combination with two primary elements including a totalizer having a series of computing wheels arranged to be variously grouped so as to afford one or more computing units of variable magnitude, and a master wheel for driving said computing wheels *seriatim*, one of said elements traveling to enable the *seriatim* registering of said master wheel with each of said computing wheels, of a traveling carriage, connections enabling the concomitant step-by-step movements of said traveling element with said carriage, and a disconnector acting during the advancing movement of the carriage and traveling element to interrupt said connections, said traveling element remaining at the point dropped when said connections are interrupted, to continue its movement in the same direction subsequently. 75 80 85 90 95

56. The combination with two primary elements including a totalizer having a series of computing wheels arranged to be variously grouped so as to afford one or more computing units of variable magnitude, and a master wheel for driving said computing wheels *seriatim*, one of said elements traveling to enable the *seriatim* registering of said master wheel with each of said computing wheels, of a traveling carriage, connections for repeatedly picking up said traveling element so that the latter may travel synchronously with the travel of the carriage, and disconnecting means for repeatedly interrupting said connections so as to drop said traveling element, said traveling element remaining in its advanced position where dropped, said connections including a plurality of pick-up elements coming into action successively to enable the successive picking up of said traveling element 100 and advancing the same an added distance 105 beyond its last position, and said disconnecting means including a series of disconnectors coming into play successively to drop said traveling element after a period of 110 travel with said carriage for each of said pick-up elements. 115 120
